CLAIM

The ornamental design for a cigar knife, as shown and described.

DESCRIPTION

FIG. 1 is a first perspective view of a cigar knife showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a perspective view of the cigar knife in an open configuration thereof.

The broken lines shown in the drawings depict portions of the cigar knife that form no part of the claimed design.
